(57) **CLAIM**

The ornamental design for an LED optic, substantially as shown and described.

DESCRIPTION

FIG. 1 is a top isometric view of an LED optic;

FIG. 2 is a front view thereof;

FIG. 3 is the view of FIG. 1, with some environmental structure removed to provide a clearer understanding of the design;

FIG. 4 is the view of FIG. 2, with some environmental structure removed to provide a clearer understanding of the design;

FIG. 5 is a rear view thereof, with some environmental structure removed to provide a clearer understanding of the design;

FIG. 6 is a top view thereof, with some environmental structure removed to provide a clearer understanding of the design; and,

FIG. 7 is a side view thereof, with some environmental structure removed to provide a clearer understanding of the design.

In FIGS. 1-5, the dot-dash broken lines circumscribing the article shown and separating solid lines from broken lines represent the bounds of the claimed design and form no part of the claimed design. In FIGS. 1-7, the remaining broken lines are illustrative of environmental structure forming no part of the claimed design.
